MULTIPLE ROLL MILL

Sven Larsson, Sandviken, Sweden

Application April 20, 1943, Serial No. 483,717
In Sweden October 11, 1941

3 Claims. (Cl. 80—38)

Multiple roll (cluster) mills of the type are known in which the working roll in each half of the rolling mill is mounted between two "backing" rolls and said backing rolls in their turn are supported by a group of rolls with larger diameter, and said last mentioned rolls are further supported by a backing roll group and so on. However, each group of backing rolls in the half of the rolling mill is usually increased by another roll, viewed from the working roll, and only the outer backing rolls are usually mounted in the roll housing and the intermediate rolls guided in their positions by resting against at least three working and backing rolls or only backing rolls.

This rolling mill construction has many disadvantages. The following ones may be mentioned: The diameter of the outer backing rolls cannot be made sufficiently large to insure a satisfactory mounting. Also the bending of said rolls through the roll pressure becomes large, due to the small diameter. Since as a consequence of this construction to a great extent one roll rests against two rolls in the two halves of the rolling mill all of the rolls in each intermediate roll group must, moreover, mutually have exactly the same diameter in order to obtain only rolling friction between the rolls. Moreover, the possibilities of supplying lubricating and cooling liquid to the intermediate rolls will not be good. The side backing rolls of the outer group in the upper part will, moreover, lie so close to the corresponding rolls in the lower part of the roll housing that the mounting of the guide casing is rendered considerably more difficult.

The purpose of the present invention is to eliminate said disadvantages. This is obtained thereby that to the outermost backing roll group is given the same number of rolls as to the outermost group but one whereby each of the rolls in the former group supports its individual group in the latter group, and thereby that the rolls in the outermost group but one are guided by bearings which in their turn are guided in such a way in the lateral direction that their rolls may be displaced by the rolling pressure toward their respective outermost backing rolls.

The invention is illustrated on the accompanying drawings, in which

Fig. 1 is a cross section and

Fig. 2 a vertical section through an eighteen-roll mill.

Fig. 3 is a sectional view through a ten-roll mill.

Fig. 4 is an alternative mounting of the rolls

of the outer backing roll group, viewed from above.

The machine shown in Figs. 1 and 2 is an eighteen-roll mill with three backing rolls in each half of the rolling mill. Only the parts of the rolling mill necessary for elucidating the invention are disclosed and described.

The working rolls 1 and 1' are driven each from its side of the rolling mill, and are guided in their 10 positions by resting against the strip, sheet, skelp or the like *a* to be rolled and against the roll pair 2, 2' and 3, 3' respectively of the first backing roll group. Each of said rolls 2, 2' is guided between the working roll and two of the rolls 4, 4', 15 4'' of the second backing roll group.

The axes of the side backing rolls 6, 4 and 2 lie in the same plane and so do also the side backing rolls 6'', 4'' and 2', compare also Fig. 3. The axes of the intermediate backing rolls 8' and 4' 20 lie in the same plane as the resultant of the roll pressure from 2 and 2' against 4'. Consequently, no lateral pressure from the roll pressure on the bearings 8, 8' and 8'' arises, and therefore said bearings only serve to guide the intermediate rolls 25 4, 4' and 4'' in the respective planes. The absence of lateral pressure also characterizes the rolling mill according to Fig. 3.

It is not shown on the drawings how the bearings 8, 8' and 8'' and so on are arranged for 30 the required displacement because different devices may be chosen for this purpose. However, the displacability is indicated in Fig. 2 by a play on both sides of the bearings in the mill housing. Said housing represents the open type. The upper part indicated by 10 is thus detachably connected with the lower part by means of bolts 11. The two parts may alternatively be hinged to one another in a way known per se so that the upper part can be swung upward to facilitate a rapid 40 opening of the rolling mill.

In the device shown in Fig. 4, which can be applied at least at the outer backing rolls, the roll is shaped like a sleeve and rotates on rollers 12, the so-called needles, around the shaft 13. 45 Thus, the roll can have stationarily mounted necks. Said mounting on so-called needles, which is known per se, is particularly suitable in the rolling mill type in question. As, thanks to this invention, the outer rolls obtain a relatively large diameter their dimensions as well as their mounting may easily be adjusted with respect to the occurring roll pressures. By providing the roll shaft with flanges 14 the needles may be guided while the flanges serve as distance 50 supports for the side pieces of the mill housing

when said side pieces are tightened by bolts 48.

Having now described my invention, what I claim as new and desire to secure by Letters Patent is:

1. A multiple roll mill, in which the working roll which is driven from the outside in the upper as well as the lower half of the rolling mill is supported by two backing rolls and said backing rolls in their turn are supported by a group of rolls of larger diameter, and said rolls are further supported by at least one further backing roll group, the outermost backing roll group above the path of the material to be rolled as well as the corresponding backing roll group below the said path having the same number of rolls as the outermost group but one, each roll in the former group supporting one roll in the latter group, the rolls of the outermost group but one each being

guided in its bearings which are displaceable radially or approximately radially towards the bearings of the respective outermost backing roll and which are suitably guided for this displacement.

2. A rolling mill as claimed in claim 1, in which the working rolls are each driven from the side of the rolling mill on which they are located and are guided in their positions by resting against 10 the material to be rolled and against the roll pair of the innermost backing roll group.

3. A rolling mill as claimed in claim 1, in which the outermost backing rolls are sleeve-shaped and mounted on so-called needles, located 15 between said backing rolls and shafts stationarily mounted in the roll housing.

SVEN LARSSON.
